UNITED STATES PATENT OFFICE.

ELIAS M. AVERILL, OF SPARTA, MICHIGAN.

COLLAPSIBLE BOX.

1,422,912.

Specification of Letters Patent. Patented July 18, 1922.

Application filed March 16, 1920. Serial No. 366,411.

To all whom it may concern:

Be it known that I, ELIAS M. AVERILL, a citizen of the United States, residing at Sparta, in the county of Kent and State of Michigan, have invented certain new and useful Improvements in Collapsible Boxes, of which the following is a specification.

My invention relates to improvements in so called collapsible boxes, and its objects 10 are: first, to provide a collapsible box that may be readily assembled for receiving articles, as vegetables, &c. for shipping; second, to provide a collapsible box that may be manufactured and sold as cheaply as an ordinary shipping box, and may be readily taken to pieces for reshipment; third, to provide a collapsible box in which the interlocking elements consist of the peculiar construction of the ends of the retaining cleats, 15 and in which the construction of all the ends of all the cleats are identically alike, and no additional mechanism is required in its construction.

I attain these objects by the construction 25 shown in the accompanying drawing, in which Fig. 1 is a plan of one of the cleats showing the manner of placing the sides of the box. Fig. 2 is a plan of a part of a box showing the corner construction, and the 30 relative form of the cleats. Fig. 3 is a perspective of the box assembled. Fig. 4 shows how two adjacent sides of the box are connected to form a right angled corner. Fig. 5 is an end view of the modified form of 35 cleat. Fig. 6 is a perspective of the modified form of box, complete. Fig. 7 is an end view of one side of the modified form of box. Fig. 8 is a sectional view of one side of the box practically upon the line 3—3 of 40 Fig. 6, and Fig. 9 is a like view with a part of another side of the box joined thereto at right angles therewith.

Similar reference characters indicate similar parts throughout the several views.

In the construction of this box I form the 45 cleats 1 twice as wide as they are thick, and cut a corner, 8, out so the ends 7 will extend beyond the shoulder. Thus the ends 7 may be lapped by each other and interlocked together as indicated in Figures 2 and 3 so that each projecting end will lock the others firmly in place and form a very rigid corner construction at all corners of the box.

The side panels 2 of this box are securely 50 attached to the inner edges of the cleats, as

shown in Figure 3 and indicated in Figures 1 and 2.

The secret of the interlocking corners of this box lies in the peculiar construction of said corners, as follows: It will be noted 55 that all of the side boards or panels 2 of this box are secured to the edges of the cleats. This is done in such a manner that in the assembled box two opposite cleats upon each side of the box are positioned flatwise, and 60 the other two on this side are positioned edgewise so that the first two cleats will rest with the sides of the extended ends 7 resting upon the edges of the extended ends 7 of the adjacent cleats with the back, or inner 65 edges of the ends 7 bearing upon the shoulder of the adjacent cleat that stands at right angles therewith, on the same end of the box, and the extended end of the, relatively, vertical cleats will be engaged between the 70 inner edges of the edgewise cleats and the shoulders of the flatwise cleats, this, in combination with the securely connected side pieces or panels 2, tends to draw the several 75 extended ends in the construction of each 80 corner of the box, so firmly together, and so firmly interlocked that the box construction becomes extremely rigid and unyielding, and, even without the cover part clamped in place the box will stand safely for filling 85 without the need of any outside retaining elements to prevent its collapse while filling. In this respect I find this box much more 90 desirable than the modified form of construction shown on Sheet 2 of my drawing, and much more simple of construction, more 95 easily assembled, and less expensive, as the cleats require but one half the material, and the construction is much more simple.

The peculiar form of the interlocking elements in this modified form of construction as shown herewith, requires the use of square cleats, in cross section, being formed with the material cut away at 8' to form shoulders *h*, *i* and *i'*, and the parts 9 and 10 beveled from *f* and *g* to the center of the end of the cleat at *e*, forming miter bearings 100 with the adjacent cleats, in three several positions. 7 represents the extended end of the cleat, and these ends are so constructed 105 that when the box is assembled each will bear upon the corresponding end of one adjacent cleat, and upon the shoulder *h* of each other adjacent cleat, thus providing an interlocking arrangement of the ends of the 110

three contacting ends of cleats at each corner of the box. Thus, the inclines *f*, *g*, *e* form perfect miter bearings at each corner of the box, with the three contacting ends 5 of the cleats, and the shoulders *h*, *i* and *i'* form retaining bearings each with the other on the several contacting ends.

Entering now, more particularly, into a description of the construction and operation of 10 the several parts of this box, 1 represents the supporting cleats, to the inner surfaces of which the enclosing panels 2 are securely attached, as with nails, cement, or other available securing devices. 1' is one of the cleats 15 likewise secured upon the cover. This cleat is divided at 3 so it may be raised into the position indicated at *c* and its ends passed by, as at *a* and *b* in Figure 4 to disconnect the locked ends of the two adjacent cleats 20 to remove the cover. 2 represents the panels or sides of the box, to which the cleats 1 and 1' are securely attached, and 2' is the cover panel, which is divided at 4, for the purpose 25 herebefore stated in connection with the cleat 1'. 5 is a spring locking device connected with one end of the cleat 1', as *j*, and temporarily connected with the other end of said cleat by means of a pin 6 so it may be sprung backwardly off of said pin, as in Fig. 30 4, to free the cleat 1' and raise it into the position indicated at *c*, as hereinbefore described. The ends of the cleats are cut away at 8' forming square bearings, and at 10 forming two beveled bearings that connect, 35 as at 9, to form miter joints between the ends of contacting cleats, the ends 7' of the cleats being made across the entire width of the cleats so it occupies the same amount of space upon the ends of the cleats as the parts 8' and 40 10, and the overlapping of this element and its peculiar contact with the corresponding elements on other cleats, and with the shoulders *h*, *i* and *i'* forms a set of locking ends 45 that are inseparable until the cover cleat has been removed as shown in the dotted lines in Figure 6, and the cover slid out of contact at the other cleat corners, when the box will fall apart without difficulty.

When it is desired to dis-assemble an 50 assembled box, the spring latch 5 is sprung off of the pin 6 and raised into practically the position indicated by the dotted lines *c*, when the divided cleat 1' may be slid endwise and disconnected from the cleats at each end 55 thereof, and the cover may then be slid backwardly, as indicated by the dotted lines *k* and *l*, be, thus, wholly disconnected from the box. In assembling the box, after the sides and bottom have been properly assembled, the 60 cover may be applied and the box firmly locked together by reversing the above stated movements of the cover and its divided cleat. In assembling the box care must be taken to arrange all of the cleats upon the outside of

the box, and in such a manner as to show 65 square panels enclosed, on all sides with the cleats, as shown in Figure 6; thus, the bottom must rest upon its cleats, the first two sides, opposite each other, must be placed with the cleats vertical of the box, and the 70 next two panels must be placed with the cleats horizontal of the box, and the top must be placed with the cleats paralleling the cleats on the bottom.

The modification herein shown and described is used simply to illustrate that the same effect may be obtained in the corner construction of boxes by various means, hence I do not desire to restrict myself closely to the construction or constructions herein 80 shown, but have made some of my claims broad enough to cover other modifications. I desire it to be understood, also, that much of the description devoted to the modified form shown applies as fully to the preferred 85 form, or to any other modification whereby the interlocking corner results may be attained.

What I claim as new in the art, is:

1. In collapsible box construction, side and 90 end panels, cleats secured to the outer sides of the panels at opposite ends thereof, said cleats made thin and broad, each end of each cleat cut away uniformly one half the width laterally and the full width longitudinally and so formed that the ends of the cleats may be interlocked at the corners of the box and assemble a rigidly constructed collapsible box.

2. In collapsible box construction, side 100 panels and end panels, cleats made twice as wide as thick and secured to one side of each panel at two opposite ends thereof, each end of each cleat uniformly cut away the exact thickness and width of the cleats and 105 arranged to interlock with each other at the corners of the box and, with the panels, form a rigidly constructed readily collapsible box having the cleats arranged to form a rigid outwardly projecting framework 110 around all sides of the box.

3. In collapsible box construction, uniformly constructed panels, each panel having a supporting cleat secured to one side at 115 each end thereof, the ends of the cleats uniformly constructed to interlock at the corners of the box and to assemble into rigid box construction, a cover having one cleat severed near the longitudinal center so it may be divided and readily inserted into, and 120 removed from the box construction, and a spring latch and catch connected with the severed cleat to readily lock it in place or remove it when assembling or dis-assembling a box.

Signed at Sparta, Michigan, March 6th 125
1920.

ELIAS M. AVERILL.
